UNITED STATES PATENT OFFICE

ELMER HEDEEN, OF BUCYRUS, OHIO

DESIGN FOR A BURIAL VAULT

Application filed August 29, 1931. Serial No. 40,958. Term of patent 7 years.

To all whom it may concern:

Be it known that I, ELMER HEDEEN, a citizen of the United States, residing at Bucyrus, in the county of Crawford and State of Ohio, have invented a new, original, and ornamental Design for a Burial Vault, of which the following is a specification, reference being had to the accompanying drawings forming a part thereof.

In the drawings, Fig. 1 is a side elevation of the burial vault showing my new design; Fig. 2 is an end elevation of the burial vault; Fig. 3 is a perspective view of the burial vault, showing my new design, on a reduced scale.

I claim:

The ornamental design for a burial vault, as shown.

ELMER HEDEEN.
